[57] CLAIM

The ornamental design for an adapter for converting
recorded video signals from one to another size cas-
sette, as shown and described.

DESCRIPTION

FIG. 1 is a front, top and right side perspective view of
an adapter for converting recorded video signals from
one to another size cassette showing my new design;
FIG. 2 is a left side elevational view;
FIG. 3 is a top plan view;
FIG. 4 is a front elevational view;
FIG. 5 is a right side view;
FIG. 6 is a rear elevational view;
FIG. 7 is a bottom plan view; and
FIG. 8 is a view similar to FIG. 1 with the cover in
open position.
